UNITED STATES PATENT OFFICE.

JAMES F. MALCOM, OF BLUFFTON, INDIANA, ASSIGNOR OF ONE-HALF TO ALLEN L. MEEKS, OF MONTPELIER, INDIANA.

OIL-VAPORIZER.

940,981.

Specification of Letters Patent. Patented Nov. 23, 1909.

Application filed May 10, 1909. Serial No. 495,122.

To all whom it may concern:

Be it known that I, JAMES F. MALCOM, a citizen of the United States, and residing at the city of Bluffton, in the county of Wells 5 and State of Indiana, have invented a new and useful Oil-Vaporizer, of which the following is a specification.

This invention relates to devices for the vaporization of crude oil for purposes of 10 fuel for steam boilers and the like.

The objects of my invention are to provide a device of the kind described which will be economical of construction, not liable to get out of order or repair, and which will 15 accomplish a vaporization of the oil and the discharge or delivery of the combustible gases therefrom, of such equable and uniform quality and quantity that the combustion therefrom will be constant and complete. 20 These and other objects which will become apparent as the specification of my invention proceeds, are accomplished by the new combination, construction and arrangement of parts described herein, illustrated 25 in the accompanying drawings, and clearly defined in the appended claims.

Similar letters of reference refer to corresponding parts throughout the several views in the drawings, in which—

30 Figure 1 is a front view of my improved oil vaporizer. Fig. 2 is a central sectional view of my improved oil vaporizer, and Fig. 3 is a side view showing my invention installed in operative position.

35 The chest A is preferably of globular form and provided in one side thereof is the threaded opening B into which is screwed the hot air pipe C. The opening D is provided in the side of the said chest opposite 40 the hot air pipe, and in the said opening D is screwed the oil inlet pipe E. Centrally between the aforesaid openings and extending at a right angle thereto are disposed the inlet steam conduit F and the conduit G.

45 Each of these conduits is formed integral with the wall of the chest A and their outer ends are threaded to receive suitable connections for the inlet pipe H, and the discharge pipe I, respectively. The inner ends 50 of the conduits F and G are so terminated with reference to each that there will be a

small distance or open space between said ends and substantially opposite to the opening D.

The novel and peculiar form, construction 55 and arrangement of parts constituting my improved vaporizer and whereby the results of my invention are accomplished, are shown plainly in Fig. 2, which will now be referred to. Provided in the conduit F is the perforation J the inner end of which is slightly flared and which leads to the perforation K in the conduit G. The mouth of this perforation K at its inner end is of diameter 60 larger than that of the mouth of the perforation J. The perforation K is of tapered form it being gradually decreased in diameter 65 to the throat L and then of gradually increased diameter to the outer end of the conduit.

In the installation of my invention into operative position the hot air pipe C is passed through the wall of the boiler M and into the firing chamber and the discharge pipe I will project into the firing 70 chamber of the boiler. In oil vaporizers wherein a jet of steam is used in combination with an ordinary inlet of air, a partial vaporization only of the oil is accomplished, the result being a fluctuating supply of 75 combustible mixture, and the consequent failure of combustion and then the dangerous uncontrolled flow of gas and of re-ignition. To accomplish the more complete and effective vaporization of the oil, I provide 80 the pipe or conduit to take the hot air from the firing chamber direct into the chest where as it mingles with the steam and oil such vaporization is effected that there is a steady and uniform delivery into the firing 85 chamber of a gas that is highly combustible and of high efficiency.

To operate my invention, the oil valve N, after the usual initial heat is generated in the firing chamber of the boiler, is opened. 95 Then steam is introduced by opening the valve O. The vaporization of the oil will commence immediately. By reason of the peculiar combination, construction and arrangement of the several parts, such action, 100 operation, and effect are effected by the steam in its passage through the perforations J

and K on the hot air and oil affected thereby, and such vaporization of the fuel is produced that the combustion in the firing chamber is uniform and complete. A clean 5 uniform and hot fire is the result, and there will be no clogging or accumulation in the vaporizer chest.

The preferable manner of installing my invention for operation is that shown in Fig. 10 1, however by reason of the improved suction through the oil pipe that is accomplished, my invention will operate successfully with the oil inlet and air inlet disposed horizontally as well as in the vertical 15 position as shown, and the oil will be drawn into the chest uniformly and correctly without reference to the location of the source of supply of the oil, whether above or below the chest.

20 I am aware that vaporizer devices have heretofore been devised wherin a blast or jet of steam has been used in combination with an oil inlet and the oil is vaporized and blown into the firing chamber of the boiler. 25 In the use of such devices as hitherto made and practiced a high pressure of steam is necessary under all circumstances, and moreover the consistency of the vaporized fuel is so variable and uncertain and the delivery of 0 same is so unsteady and unreliable that frequent failure of the combustion occurs and explosions with their attendant dangers are frequent.

My invention is of especial utility for the 5 utilization of crude or refuse oil of the heavier grades, and by my invention such a uniform and equable vaporization of such crude or refuse oil and such steady and unvarying delivery of the combustible mixture or gas are accomplished that the combustion from such vaporization is complete, and there will be no precipitation on the flues and inner lining of the firing chamber, so objectionable where the fuel is not completely vaporized.

By the preferable arrangement and connection of the steam pipe H with a T-connection P having the removable plug Q as shown in Fig. 3, easy access to the interior 50 of the perforation K is afforded. The object of this arrangement is to render easy the dislodging by a suitable implement of any hard foreign substance such as a fragment of wood or mineral or rock as might 55 occur, in the refuse oil being used.

What I claim as my invention and desire to secure by Letters Patent of the United States, is—

1. In a device of the kind described, the 60 combination of a hollow chest, a conduit passed through the said chest and being divided transversely upon the interior of said chest to form an inlet conduit and an outlet conduit, the bore of said inlet conduit being

flared to increased diameter at the inner end 65 of said conduit, and the bore of the outlet conduit having a mouth of diameter larger than that of the inlet conduit, an oil inlet through the wall of said hollow chest at a point opposite the space between the interior 70 ends of the inlet and outlet conduits, and an air inlet through the wall of said hollow chest at a location aside from said space between the ends of the aforesaid conduits.

2. In a device of the kind described, the 75 combination of a hollow chest, a conduit passed through the said chest and being divided transversely upon the interior of said chest to form an inlet conduit and an outlet conduit, the bore of said inlet conduit being 80 flared to increased diameter at the inner end of said conduit, and the bore of the outlet conduit being tapered to smaller diameter and then flared to increased diameter at the outer end of said outlet conduit, having a 85 mouth of diameter larger than that of the inlet conduit, an oil inlet through the wall of said hollow chest at a point opposite the space between the interior ends of the inlet and outlet conduits, and an air inlet through 90 the wall of said hollow chest at a location aside from said space between the ends of the aforesaid conduits.

3. A device of the kind described, comprising a globular chest having an inlet conduit and an outlet conduit formed integral with the opposite walls of said chest, the inner ends of said conduits being so disposed as to register with each other but there being an open space between them and aside 100 from the center of said chest, the bore of said inlet conduit being flared to increased diameter at its inner end, and the bore of the outlet conduit having a mouth that is of diameter greater than that of the bore of the 105 inlet conduit, and which said last named bore is tapered to smaller diameter and then flared to increased diameter toward the outer end thereof, an oil inlet through the wall of said chest at a point substantially opposite 110 the open space between the inner ends of said conduits, and an air inlet through the wall of said chest at a point aside from the said open space, substantially as described.

4. In a crude oil vaporizing apparatus for 115 steam boilers, the combination of a hollow chest having an oil inlet and an air inlet therein, a conduit passed through the said chest and being divided transversely upon the interior of said chest to form an inlet conduit and an outlet conduit, the bore of 120 said inlet conduit being flared to increased diameter at its inner end, and the bore of the outlet conduit having a mouth that is of diameter greater than that of the bore of the 125 inlet conduit, and which last named bore is tapered to smaller diameter and then flared to increased diameter toward the

outer end of said outlet conduit, a firing chamber, a pipe connected to the outer end of the outlet conduit and extended into the said firing chamber, a fire box, and a pipe leading from the fire box of the boiler into the air inlet, substantially as and for the purposes described.

In testimony whereof I sign my name to this specification in the presence of two subscribing witnesses.

JAMES F. MALCOM.
